[57] CLAIM

The ornamental design for a shower control handle, as shown and described.

DESCRIPTION

FIG. 1 is a front perspective view of our new design for a shower control handle;

FIG. 2 is a front view thereof;

FIG. 3 is a left side view thereof, the right side being the same as the left side;

FIG. 4 is a rear view thereof;

FIG. 5 is a top view thereof; and,

FIG. 6 is bottom view thereof.

The broken lines in the drawings are for illustrative purposes only and form no part of the invention.
